UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION.

SELF-OPENING DIE HEAD.

Substitute for application Serial No. 129,867, filed August 18, 1926. This application filed May 18, 1928.
Serial No. 278,836.

My invention relates to an improvement in self-opening die-heads, the object being to produce a simple, compact, reliable and durable fixture constructed with particular reference to being tripped from the outside by an extraneous abutment or from the inside through the medium of the work itself, according to the nature and exigency of the use of the fixture.

With these ends in view, my invention consists in a self-opening die-head characterized by having a tripping-sleeve adapted to be tripped by an abutment external to the fixture and also to be internally tripped through the medium of the work being threaded and axially movable upon an operating-sleeve carrying parallel chaser operating-rods, the forward ends of which have cam-like connection with the respective chasers for the positive radial movement thereof in chaser-receiving slots formed in the forward end of the die-body.

My invention further consists in a self-opening die-head characterized as above and having certain details of construction and combinations of parts as will be hereinafter described and pointed out in the claims.

In the accompanying drawings:

Fig. 1 is a view in side elevation of a self-opening die-head embodying my invention;

Fig. 2 is a view thereof in front end elevation;

Fig. 3 is a view thereof in transverse section on the line 3—3 of Fig. 1;

Fig. 4 is a view of the die-head in central longitudinal section showing the fixture closed, preparatory to a threading operation;

Fig. 5 is a corresponding view showing the parts of the die-head in the positions due to them at the conclusion of a threading operation and at the instant of the disengagement of the locking-pawl from the locking-rod and before the operating-sleeve has been moved rearward which will instantly follow;

Fig. 6 is a corresponding view showing the parts of the die-head in the positions due to them at the conclusion of the rearward movement of the operating-sleeve which effects the retraction of the chasers;

Fig. 7 is a view of the die-head in transverse section on the line 7—7 of Fig. 1;

Fig. 8 is a broken detail sectional view on the line 8—8 of Fig. 2;

Fig. 9 is a corresponding view on the line 9—9 of Fig. 2; and

Fig. 10 is a corresponding view on the line 10—10 of Fig. 2.

In carrying out my invention as herein shown, I employ a skeleton die-body 15 having an integral tubular shank 16, an operating-sleeve 17 having axial movement on the said die-body and shank, and a tripping-sleeve 18 having axial movement upon the said operating-sleeve. At its forward end the said die-body is formed with four equidistant radial slots 19 respectively receiving four chasers 20 having their inner ends toothed as at 21 and their outer ends cut away as at 22 to clear the forward end of the operating-sleeve 17, as clearly shown in Fig. 8. Each of the said chasers is formed in one of its side walls with an angular slot 23 receiving an angular lug 24 formed at the forward end of a chaser operating-rod 25 having reciprocating movement in a bore 26 in the said body, whereby the chaser is positively moved radially into its retracted and cutting positions. At their rear ends the four rods 25 are secured by pins 27 (Fig. 3) to the operating-sleeve by which they are carried.

Helical springs 28 located in bores 29 entering the rear end of the die-body 15 impinge at their rear ends upon the forwardly-facing shoulder 30 of the operating-sleeve 17 and exert a constant effort to move the said sleeve rearward and so effect the positive retraction of the chasers through the rods 25.

To lock the operating-sleeve 17 in its forward position, in which the chasers are held in their cutting positions against the tension of the springs 28, I employ a locking-pawl 31 hung in a slot 32 in the operating-sleeve 17 upon a pin 33 and formed at its outer end with a bevel 34 for co-action with the inclined forward wall 35 of a segmental notch 36 in the inner periphery of the tripping-sleeve 18. The inner edge of the inner end of the said pawl 31 is cut away for clearance as at 37 and co-acts with a locking-notch 38 in the rear end of a locking-rod 39 located in a bore 40 in the die-body 15 and held against rotation therein by a transverse pin 41. The forward end of the rod 39 is bored and tapped for the reception of an adjusting screw 42 entering the die-body 15 and the bore 40 thereof from its forward face,

whereby provision is made for varying the diameter of the cut in the work.

A pawl-spring 43 in a recess 44 in the operating-sleeve 17 engages with the inner edge of the pawl 31 in position to exert a constant effort to turn the same on its pin 33 so as to maintain it in engagement with the locking-rod 39, whereby the chasers are locked in their cutting positions.

- 10 A stop-screw 45 entering into the operating-sleeve 17 through a countersunk opening 46 in the tripping-sleeve 18 projects into an elongated slot 47 in the periphery of the shank 16 and acts to limit the axial movement of the operating-sleeve upon the die-body. A key 48, interposed between the operating-sleeve 17 and the tripping-sleeve 18, prevents their relative rotation.

At its rear end the tripping-sleeve 18 is formed with an annular groove 49 designed to receive a yoke or other suitable abutment not shown, generally positioned in the machine in which the die-head is used. This groove 49 thus provides for the outside tripping of the die-head by an abutment external to it and mounted independently of it. For the internal tripping of the die-head through the medium of the work itself, rather than of such an external abutment as described, I provide a tripping-rod 50 centrally located within the die-body 15 in a bushing 51 fitting into and having limited reciprocating movement in a central bore 52 therein and held in any desired position with respect to the said bushing by means of a coupling-screw 53 extending radially between the bushing 51 and the tripping-sleeve 18, as shown in Fig. 4. To provide for the clearance of the screw 53 and for its lateral reciprocation, the body 15 is formed with a radial slot 54 and the operating-sleeve 17 with a corresponding slot 55. At its forward end the rod 50 is provided with a T-head 56 secured in place by a pin 57 for insuring the actuation of the rod 50 by articles having a bore of larger diameter than the diameter of the rod, such as some gauges of pipe.

As shown in Figs. 1 to 4 inclusive, my improved die-head is, in its closed position, ready for a threading operation, at which time the locking-pawl 31 has its reduced edge 37 entered into the locking-notch 38 of the locking-rod 39, whereby the operating-sleeve 17 is held in its forward position against the tension of the springs 28 and the chasers held in their contracted or cutting positions. At this time, also, the tripping-sleeve 18 is held at the limit of its forward movement, as shown in Fig. 4. At a predetermined point in the threading operation, during which the die-head is usually moved toward the work, though the work may, if preferred, be moved into the die-head, the tripping-sleeve 18 is arrested by the yoke, or other

suitable abutment, positioned in the usual and well-known manner, according to the character of the work to be done in the machine in which the die-head is being used. When the tripping-sleeve is thus arrested, the inclined forward wall 35 of its segmental notch 36 operates upon the beveled outer edge 34 of the locking-pawl to rock the same upon its pin 33, whereby the reduced upper edge of its inner end is disengaged from the locking-notch 38 in the locking-rod 39, as shown in Fig. 5, at which time the operating-springs 28 re-assert themselves to move the operating-sleeve rearward with respect to the die-body. During this rearward movement of the operating-sleeve the chaser-operating rods 25 effect the movement of the chasers into their retracted positions, as shown in Fig. 6, in which the stop-screw 45 is shown as having been brought to engage with the rear wall of the slot 47 in the shank 16.

In case it is decided to have the die-head automatically tripped through the medium of the work itself, instead of through the medium of an external abutment, as above described, the screw 53 is loosened and the tripping-rod 50 longitudinally moved in the bushing 51 as becomes necessary to trip the die-head at the predetermined point of its travel demanded by the given work to be done, after which the screw 53 is tightened so as to form a rigid coupling between the tripping-rod 50 and the tripping-sleeve 18.

It will thus be seen that my improved die-head may be tripped by an external abutment, or automatically tripped through the medium of the work itself, as may be found most convenient.

For the removal of the chasers, an ordinary screw-driver is introduced through the opening 46 in the tripping-sleeve and the stop-screw 45 backed out until its inner end clears the rear end of the slot 47 in the shank 16, thus permitting the operating-sleeve 17 to slide rearward on the body 15 sufficiently to permit the chasers 22 to be radially extracted from chaser-receiving slots 19.

I claim:

1. A self-opening die-head having a body, chasers, an operating-sleeve, chaser operating-rods carried by the said sleeve extending forwardly into said die-body and having cam-connection with the said chasers for positively moving the same radially in either direction, operating-springs, locking means for holding the sleeve in its forward position against the tension of the said springs, a tripping-sleeve axially movable upon the said operating-sleeve, co-acting with the said locking means for releasing the operating-sleeve to the action of the said springs and adapted to be engaged by an external abutment for operation thereby, and internal tripping-means centrally located within the fixture in position to be operated by the work being

threaded and coupled with the said tripping-sleeve for operating the same.

2. A self-opening die-head having a body, radially-movable chasers mounted in the forward end thereof, an operating-sleeve axially movable upon the said body, means connecting the said sleeve with the said chaser for the positive operation thereof in either direction, a locking-pawl mounted in the said sleeve, a locking-rod mounted in the said body in position to be engaged by the said pawl, operating-springs interposed between the body and sleeve and relatively moving the

same for the retraction of the chasers, a tripping-sleeve adapted to be operated by an external abutment and also to operate the said pawl to disengage the same from the said operating-rod to permit the opening of the fixture, and internal tripping-means coupled with the said sleeve for the operation thereof and having a member centrally located within the die-head for direct engagement by the work itself. 15

In testimony whereof, I have signed this specification.

ALBERT F. BREITENSTEIN.
